Primary Examiner—Donald P. Walsh**Assistant Examiner—Caron D. Veynar****Attorney, Agent, or Firm—Thomas J. Roth; Stephen D. Krefman; Thomas E. Turcotte****[57]****CLAIM**

The ornamental design for a housing for a hand-held mixer, as shown and described.

DESCRIPTION

FIG. 1 is a top front perspective view of the housing for a hand-held mixer showing my new design;
 FIG. 2 is a front elevational view thereof;
 FIG. 3 is a right side elevational view thereof, the left side elevational view being a mirror image thereof;
 FIG. 4 is a top plan view thereof;
 FIG. 5 is a rear elevational view thereof; and,
 FIG. 6 is a bottom plan view, the beater receptacles deleted for ease of illustration.
